FIG. 1 is a rear perspective view of a braided hair attachment for a helmet, showing my new design in an attached configuration;

FIG. 2 is a front perspective view thereof, illustrated in a straight configuration;

FIG. 3 is a front elevational view of FIG. 2;

FIG. 4 is a rear elevational view of FIG. 2;

FIG. 5 is a right-side elevational view of FIG. 2;

FIG. 6 is a left-side elevational view of FIG. 2;

FIG. 7 is a front elevational view of FIG. 2; and,

FIG. 8 is a rear elevational view of FIG. 2.

The broken lines showing a helmet in FIG. 1 depict environmental matter and form no part of the claimed design.
